CYLINDER HEAD

Glenn D. Angle, Thomaston, Conn., assignor to
The New Britain Machine Company, New
Britain, Conn., a corporation of Connecticut

Application October 23, 1946, Serial No. 705,189

4 Claims. (Cl. 123—41.69)

1

My invention relates to cylinder heads for reciprocating internal combustion engines.

It is an object of my invention to provide an improved cylinder head for reciprocating engines of the valve-in-head type.

It is another object to provide an improved cylinder head having greater capacity for life than conventional cylinder-head arrangements.

It is, in general, an object to provide an improved cylinder head that will be simple to maintain and adaptable to mass production at low unit cost.

Other objects and various further features of the invention will occur to those skilled in the art from a reading of the following specification in conjunction with the accompanying drawings. In said drawings:

Fig. 1 is a plan view of a cylinder head incorporating features of the invention;

Figure 2 is a side elevation of the cylinder head of Fig. 1; and

Fig. 3 is a vertical section taken substantially in the plane 3—3 of Fig. 1.

Broadly speaking, my invention contemplates a valve-in-head type cylinder head in which valve ports and valve-receiving guides are so arranged that, when the head is affixed to a cylinder or engine block in a first manner, one system of ports and valves may serve for the inlet of un-combusted mixtures while another system of ports and valves serves for the exhaust of combusted gases. Alternatively, when fixed to the cylinder or engine block in a second manner, the first system of ports and valves may serve the exhaust function while the second system of ports and valves would serve as an inlet for combustible mixtures. This alternative functioning of the two valve-port systems permits use of a cylinder head for a maximum period of life. For example, when the exhaust-valve system including its seat and guide may have become warped or excessively worn due to extended use, the cylinder head may be reversed to its alternate manner of mounting upon a cylinder block, so that the relatively un-worn passages and seat means (previously at the inlet) may subsequently be employed for exhaust purposes.

In the specific form to be described, the cylinder head is of generally circular plan-form, and both of the valve-port systems are alike and symmetrically disposed diametrically opposite each other—the center of the plan-form serving as a center of symmetry. Securing means such as stud-receiving bores are provided in pairs which are also diametrically opposed about this same

2

center of symmetry. In addition all cooling fins, spark-plug holes, etc. are also preferably arranged for diametrical symmetry about the central axis. With such a construction it is possible, with a 180-degree rotational displacement of the cylinder head about its center of symmetry, to reverse the functions of the respective valve-port systems without changing either of the engine manifold systems or either of the valve-actuator mechanisms (e. g. tappets).

Referring to the drawings, my invention is shown in application to a cylinder head which may be employed for one of the cylinders of a radial aircraft engine. The cylinder head is made from a single head block 5 formed preferably with a number of outwardly extending cooling fins 6. The lower part of the block 5 is internally crowned to define a chamber 7 along the upper surface of which inlet and exhaust valves may function. The lower part of the chamber 7 is open to the cylinder (not shown) to which the head 5 is to be mounted, and the lower circumferential confines of the chamber 7 preferably comprise an annular ring having a flat surface 8 for sealing abutment with the cylinder block. Stud bolts 9 may serve for securing the head 5 to the cylinder block. The elements which have thus far been described are well known and form no part of my invention.

In accordance with the invention, the design of the head block 5 incorporates an axis of symmetry which in the form shown is centrally located and generally normal to the plane of fit of the cylinder head to the cylinder block. Each functional element is preferably provided in duplicate, and these duplicates are paired, with each element of a pair arranged diametrically opposite the other about the center of symmetry 10. Thus, two systems of gas ports 11—12, and two systems of valve guides 13—14 and seats 15—16 for cooperation with these ports 11—12, may be provided in the cylinder head in accordance with the principles indicated above. In the form shown, the ports 11—12 are diametrically opposite each other with respect to the center of symmetry 10 and this arrangement permits attachment of the port system 11 to one manifold, say to the inlet manifold system (not shown); on the other hand, the port system 12 faces to the other side of the cylinder head 5 in position for attachment with another manifold, say the exhaust manifold system (also not shown). While the valve guides 13 and 14 may be inclined to the axis of symmetry 10, the inclination with respect to this axis is preferably symmetrical, so that valves 17—18 supported in these guides may present

symmetrically placed tappet-engaging surfaces 19-20 to the actuator mechanism (not shown) for the valves 17-18.

Further in accordance with the above-indicated principles of symmetry about a central axis 10, dual spark-plug-receiving apertures 19-20 may be provided at diametrically opposed locations. Also, pairs of stud-receiving bores 21-22 and 23-24 may be located opposite each other and symmetrically about the axis 10. In addition the cooling fins 6 about the two port systems are preferably diametrically symmetrical about the same axis of symmetry, so that, regardless of the port used for exhaust purposes, cooling efficiency may be the same.

It will be seen that with the arrangement described, the cylinder head 5 may be affixed to a cylinder block as by passing the studs 9 into the cylinder block and by receiving studs or other bolt means through the bores 21, 22, 23, 24. In this position the valve port 11 may be connected say to the inlet manifold system of an engine, and the valve guide 13 may receive a valve 17 positioned for control by an inlet valve-actuating mechanism or tappet (not shown). Similarly, the valve port 12 may be connected to the exhaust manifold system for the engine, while a valve 18 supported in the guide means 14 may be actuated by an exhaust-valve-actuating mechanism. After prolonged use of the engine with the head 5 bolted in the manner described, the seat 16 or other parts of the exhaust-valve system may become excessively worn. In order materially to increase the life of the cylinder head, it may be replaced upon its cylinder block in a 180-degree reversed orientation. After such relocation of the head 5 with respect to its cylinder block, it will be clear that valves 17 and 18 (supported in guide means 13 and 14) will still be suitably positioned for co-operation with the valve-actuating means of the engine but that the port 12 would then serve as an inlet and the port 11 as an exhaust. It will be noted that, even though the exhaust function is carried out in the opposite port (after reversal), the symmetrical arrangement of the fins 6 (as shown) makes possible the same cooling efficiency as obtained before reversed mounting of the head.

It will be appreciated that I have described a relatively simple cylinder-head construction which may materially extend the service customarily expected of a cylinder head. This increase in life is obtained with a construction that is inherently no more costly than present arrangements. The maintenance operation required to extend the life of the cylinder head is clearly of the simplest sort, there being no need in any way to alter either of the manifold systems of the engine or either of the valve-actuating mechanisms.

While I have described my invention in detail for the preferred form shown, it will be understood that modifications may be made within the scope of the invention as defined in the claims which follow.

I claim:

1. In a removably attachable cylinder head for a valve-in-head engine, a head block including a substantially flat bottom surface sealingly to be applied to a cylinder block, two planes of symmetry substantially normal to said bottom surface, said head block having two substantially alike independent manifolding duct systems having openings to both sides of said planes of symmetry, one of said duct systems being disposed symmetrically with respect to the other of said

duct systems about said planes of symmetry, like cooling means for each of said duct systems, said head block including means for securing the same to a cylinder block, said securing means comprising means oppositely and symmetrically disposed about said planes of symmetry, whereby upon a 180-degree reversal of the positioning of said head block upon a cylinder block the function previously performed by one of said duct systems may be performed by said other of said duct systems and the function previously performed by the other of said duct systems may be performed by said one, all without impairment of cooling efficiency in either of said positions.

2. In a cylinder head for removable attachment to a cylinder block, a head block having a plan-form generally symmetrical about each of two planes of symmetry intersecting to define a central axis of symmetry, two substantially alike valve-receiving means disposed diametrically symmetrically about said central axis, valve-port means associated with each of said valve-receiving means and disposed diametrically symmetrically about said central axis, cooling means for each of said valve-port means and diametrically symmetrically disposed about said axis, and securing means for holding said head on a cylinder block, said securing means being disposed diametrically symmetrically about said axis, whereby for one secured position of said head on a cylinder block an intake valve may be operated in one of said valve-receiving means and an exhaust valve may be operated in the other of said valve-receiving means, and whereby for an oppositely secured position of said head on said cylinder block an intake valve may be operated in said other valve-receiving means and an exhaust valve may be operated in said one valve-receiving means, and further whereby the cooling efficiency of said head may be the same in both the possible orientations of said head.

3. A cylinder head according to claim 2, in which said securing means comprises pairs of diametrically opposed bolt-receiving bores through said block.

4. A cylinder head according to claim 2, in which said block has a pair of spark-plug receiving apertures diametrically opposed across said central axis.
